SUPPORT, CORD REEL, AND LATCH FOR
SUCTION CLEANERSMelvin H. Ripple, Canton, Ohio, assignor to The
Hoover Company, North Canton, Ohio, a cor-
poration of Ohio

Application October 18, 1950, Serial No. 190,797

8 Claims. (Cl. 15—323)

1

This invention relates to suction cleaners and more particularly to a tank or canister type cleaner in which suitable cleaning tools may be connected to the motor-fan-filter unit by means of a flexible hose.

More specifically, according to the present invention, a tubular cleaning body is supported for movement over a surface by a pair of supporting skids at one end and by a single, centrally located skid at the other end. All of the skids are upwardly sloped at their forward ends and the pair of rear supporting skids are made reentrant at their rear ends so that the conductor cord for conducting electricity to the power unit may be wound thereon. The single skid at the opposite end of the cleaner is movably attached to the casing so that its free end may be moved away from the casing to form complementary means at the front end of the casing about which the conductor cord may be wound. The single supporting skid is curved downwardly from the body of the casing and has its free end normally positioned against the casing which may be moved away therefrom during the cord winding operation.

According to another feature of the present invention a removable end cap is provided for the casing at the end adjacent the single movably mounted supporting skid, and movement of the skid relative to the casing releases the latch mechanism which latches the end cap to the casing.

According to another feature of the present invention the single skid is movable to one position relative to the casing to permit the winding of the cord about the skids without releasing the end cap latch and is movable to a second position relative to the casing to release the latch.

Other objects and advantages of this invention will become apparent as the description proceeds when taken in connection with the accompanying drawings in which:

Figure 1 is a side view of a tank or canister type cleaner showing the present invention applied thereto;

Figure 2 is an end view of the cleaner of Fig. 1; and

Figure 3 is a cross-sectional view taken on line 3—3 of Fig. 2 looking in the direction of the arrows.

Referring to the drawings the reference numeral 10 represents the casing of a tank or canister type cleaner supported for movement over a surface by two rear skids 11 and 12 and a single front skid 13 and is adapted to be carried about by a carrying handle 14.

2

The exhaust or blower end of the casing 10 is closed by a blower end cap 15 and the suction end is closed by a suction end cap 16.

Enclosed within the casing 10 is a motor-fan-filter unit 9 well known to the art. In such units the motor-fan unit is positioned adjacent the blower end cap 15 and a filter bag is removably supported adjacent the suction end cap 16 and is adapted to be periodically removed so that the filter can be cleaned or replaced. One end of a suction hose is adapted to be connected to the female connector 17 and its other end attached to any suitable suction cleaning tool whereby the dirt removed by the cleaning tool will be deposited in the filter bag within the casing behind the end cap 16. For that reason the suction end cap 16 is so assembled to the casing 10 as to be readily removable therefrom.

The top front of the casing 10 is provided with an upwardly opening socket 18 adapted to receive a lug 19 carried by the end cap 16. The lower edge of the end cap 16 is clamped to the open end of casing 10 by a mechanism to be presently described. A gasket 20 lies between the end cap 16 and the end ring of the casing 10 to seal the joint between them.

Referring to Fig. 3 the skid 13 is pivoted to the bottom central portion of casing 10, to the rear of end cap 16, as at 21. The skid 13 is biased clockwise by a spring 22 so that its end 23 is normally held against the bottom wall of casing 10 immediately to the rear of end cap 16. Inwardly of the pivot 21 the skid 13 is provided with an overhanging flange 24 which, under certain conditions, is adapted to contact the rear end of an end cap latch lever 25, pivoted to the casing 10 at 26 and is spring-biased counter-clockwise by a spring 27. At its forward end the latch lever 25 is provided with a hook 28, operatively engageable with a pin 29 suitably carried by the end cap 16 near its bottom edge.

As previously stated, the end 23 of skid 13 is normally held against the bottom wall of the casing 10 by spring 22. It is also latched in that position by a detent spring 30 having a hump 31, below which a protuberance 32 on skid 13 is positioned when the end 23 of skid 13 rests against the bottom wall of casing 10. Detent spring 30 is also provided with a recess 33 in which the protuberance 32 is positioned in an intermediate position of the skid 13 in which its end 23 is separated from the bottom wall of casing 10, whereby the loops of the conductor cord 34 may be easily wound beneath the end 23 of skid 13 and into the space between the skid 13 and the bottom wall of the casing 10.

The detent spring 30 is also provided with a hump 35 above which the protuberance 32 is adapted to be positioned when the skid 13 is in latch releasing position. When the skid 13 is moved to such a position its overhanging flange engages the rear end 36 of lever 25 to pivot the lever clockwise and raise the hook 28 from behind the pin 29 and thus release the end cap for removal.

The rear skids 11 and 12 are reentrant forwardly as shown at 37 (Fig. 1) and also reentrant inwardly at 38 and 39 (Fig. 2) whereby the conductor cord 34 may, in cooperation with skid 13, be supported in its wound condition.

Operation

If it is desired to merely wind the cord 34 about, or to unwind the cord 34 from the skids 11, 12, and 13, the skid 13 is pulled downwardly to a position in which the protuberance 32 engages in recess 33 whereby the end 23 of the skid will be spaced from the bottom wall of the casing 10 to permit the easy looping of cord 34 between the skid 13 and the casing 10.

If it is desired to release the end cap 16, as when a filter bag needs cleaning or replacement, the skid 13 is turned further counter-clockwise from the dotted line position of Fig. 3, to bring the protuberance behind the hump 35 of spring 30. In such a position the flange 24 of skid 13 will have engaged the end 36 of latch lever 25 to pivot it clockwise and remove the hook 28 from behind the pin 29 and thus release the suction end cap 16 for removal from the casing 10.

While I have shown but a single embodiment of my invention it is to be understood that that embodiment is to be taken as illustrative only and not in a limiting sense. I do not wish to be limited to the particular structure shown and described but to include all equivalent variations thereof except as limited by the scope of the claims.

I claim:

1. A tank type suction cleaner comprising, an elongated body, a pair of rear supports and a single front support for supporting said body for ambulatory movement, said rear supports being reentrant forwardly and inwardly to constitute rear storage hooks for a conductor cord, said front support being pivoted to said body on a horizontal axis and positioned to form a space between itself and said body to constitute a front storage space for said conductor cord, one end of said front support being movable away from said body upon pivotal movement of said front support about its pivotal axis.

2. A cleaner as in claim 1 including spring latch means for holding said one end of said

front support away from said body during the cord winding operation.

3. In a suction cleaner, an elongated tubular open ended body, a power unit within said body, a conductor cord for conducting electricity to said power unit, an end cap secured to an open end of said body, latch means for detachably securing said end cap to said open end, first supporting means at the end of said body opposite said end cap, second supporting means at the end cap end of said body, said second supporting means being U-shaped and having one leg thereof of movably secured to said body so that its free end rests against said body adjacent said end cap whereby said conductor cord may be wound beneath said second supporting means upon movement of the free end of said second supporting means away from said body and means actuated by movement of the free end of said second supporting means away from said body for releasing said latch means.

4. In a suction cleaner according to claim 3 in which said first supporting means is also formed to have said conductor cord wound thereon for storage purposes.

5. In a suction cleaner according to claim 3 in which said second supporting means is spring-biased so that its free end is held against said body.

6. In a suction cleaner according to claim 3 in which movement of the free end of said second supporting means away from said body to one position permits the winding of said cord thereon and movement thereof to a second position away from said body releases said latch means.

7. In a suction cleaner according to claim 6 including a spring latch for holding said first supporting means in its cord winding position and permitting movement thereof to its latch releasing position.

8. In a suction cleaner according to claim 3 in which said first supporting means comprises a pair of skids having their forward ends sloped upwardly and forwardly to constitute runners and their rear ends reentrant inwardly and forwardly to constitute supporting means for said conductor cord.
